UNITED STATES PATENT OFFICE.

HAROLD FREDERICK NORTON, OF NEWPORT NEWS, VIRGINIA.

BOAT-DAVIT.

1,071,783.

Specification of Letters Patent.

Patented Sept. 2, 1913.

Application filed November 29, 1912. Serial No. 734,106.

To all whom it may concern:

Be it known that I, HAROLD F. NORTON, a citizen of the United States, residing at Newport News, in the county of Warwick 5 and State of Virginia, have invented certain new and useful Improvements in Boat-Davits, of which the following is a specification.

This invention comprises a davit and 10 mechanism for operating it to lift a boat from the deck of a vessel and swing it outboard into position to be lowered into the water, of the general type shown and described in my prior U. S. Patent, No. 15 1,011,477, dated December 12, 1911.

As in the above-mentioned patent, the davit is operated by hand-mechanism comprising a non-revolute member pivoted to the davit between its ends and a revolute 20 member journaled in a bearing of a deck-stool; the non-revolute member carrying a nut, and the revolute member having a long screw entering the nut.

It has been found that where there is rigidity of the operating parts against lateral and twisting movement of the davit, the screw and the nut into which it turns are sometimes subjected to cramping strains, when, for some reason, the davit-arm is 30 moved or bends in directions at an angle to the arc of normal oscillation of the screw, or when the davit-arm undergoes slight twisting from the torsional strains imposed upon it.

35 The object of the present invention is to provide stool and davit connections for the operating screw and its nut, sufficiently rigid, and yet of such construction as to eliminate strains upon said screw and nut, 40 due to any perverse movement or twisting of the davit-arm.

The apparatus is shown in the accompanying drawing, in which—

Figure 1 is a side elevation of the davit 45 and its operating mechanism; Fig. 2 is an end elevation of the same, viewed from inboard; Fig. 3 is an end elevation showing in detail the bearings of the operating-screw, viewed from inboard; and Fig. 4 is 50 a sectional side elevation of the operating members, on a larger scale.

The apparatus illustrated comprises a davit arm 1 of channel steel, pivoted at its lower end 2 to the deck of the vessel at the 55 gunwale, and having a curved and narrowed upper end 3, the tip of which is bent down-

ward and has a hole 4 to receive the hook of the fall-block. A cleat 5 for the block-rope is secured to the lower end of the arm. A cylindrical pivot 6 is fixed to the davit arm toward its lower end, and upon this is swiveled the eye of a collar 7. This collar is provided with a lateral extension 8 having a cross-bore 9 therethrough, adapted to receive a pivot-pin 10. The pivot-pin is 60 engaged by the upper and lower journal-eyes 11^a of a yoke 11, which carries the tubular sheath 12 and the integral nut 12^a, of the non-revolute operating member. A cap 12^b, within the yoke 11, closes the outboard end of the tubular member, to exclude water and dirt and retain a lubricant. The nut 12^a receives the long screw of the revolute member 13, a stop-nut 13^a being fixed on the inclosed end of the screw. A 65 hand-crank 13^b is removably attached to the revolute member at its outer end. A bushing 14 is fixed on the revolute member 13 near its inboard end, being screwed thereon against a thrust-nut 15, and held against 70 accidental displacement by a check-collar 16. Upon the bushing 14 is mounted a collar 17, having oppositely-disposed pintles or trunnions 18, and suitable washers 17^a may be interposed between the bushing and 75 the thrust-nut and the collar 17. A yoke-member 19 and a cap-plate 20 are provided with bearings 21 and 22, respectively, in which are journaled the pintles 18 of the collar 17, washers 22^a being interposed, if 80 desired. The yoke-member 19 is provided with rearwardly-extending portions 23 and 24, having eyes adapted to register with the eyes 25 and 26 of the steel bearing-pads 27 and to receive the bearing-pins 28 (Figs. 1 85 and 3). The bearing-pads 27 are secured to a deck-stool 29. This stool is built of structural steel, and comprises a vertical member 29^a and an inclined member 29^b, secured together at their upper ends and 90 riveted at their lower ends to a channel-beam 30, inclosing a wood beam 31 which is secured to the deck-sheathing 32. A bracket 33 is secured to the channel-member 30 near the gunwale, and a bolt 34 serving 100 as the pivot for the lower end of the davit extends through and is clamped in the two wings of this bracket.

The operation of the device is similar to that of my former patent, and is obvious. 110 A pair of these davits and operating mechanisms is provided for each boat, and require

merely that two men, one at each stool, rotate the revoluble members by means of the hand-cranks. As the davits are shifted outward, the boat rises slightly and is lifted 5 out of the chocks.

It will be seen that by providing the several bearings for the operating-members, some at right angles to the others, provision is made for universal movement which will 10 prevent strains due to perverse movement of the davit-arm from having a deleterious effect upon the operating-screw or its tubular nut.

I claim:

15 1. A davit supported by a pivot at its lower end, and means for oscillating said davit comprising two substantially horizontal members connected by a nut and long screw, one member being non-revoluble and 20 directly swiveled to said davit intermediate its ends, the other member being revoluble, and a fixed deck-stool having a bearing swiveled for universal movement in which said revoluble member is thrust-journalized, 25 its outer end extending through the bearing and provided with means for effecting rotation.

2. A davit supported by a pivot at its lower end, and means for oscillating said 30 davit comprising two substantially horizontal members connected by a nut and long screw, one member being non-revoluble and directly swiveled for universal movement to said davit intermediate its ends, the other 35 member being revoluble, and a fixed deck-stool having a bearing swiveled for universal movement in which said revoluble member is thrust-journalized, its outer end extending through the bearing and having means 40 for effecting rotation.

3. A davit supported by a pivot at its

lower end, and means for oscillating said davit comprising two substantially horizontal members connected by a nut and long screw, one member being non-revoluble and 45 directly swiveled for universal movement to said davit intermediate its ends, the other member being revoluble, a fixed deck-stool provided with a swiveled bearing, said revoluble member being thrust-journalized in said swiveled bearing and extending through the bearing and provided with means for effecting rotation.

4. A davit supported by a pivot at its lower end, a fixed deck-stool, and means for oscillating said davit comprising two substantially horizontal members, one of which is revoluble and the other non-revoluble, connected to each other by a nut and long screw, said members being pivoted, one to the davit and the other to the deck-stool, the revoluble member thrust-journalized in a bearing swiveled for universal movement.

5. A davit supported by a pivot at its lower end, a fixed deck-stool, and means for oscillating said davit comprising two substantially horizontal members, one of which is revoluble and the other non-revoluble, connected to each other by a nut and long screw, said members being pivoted, one to the davit and the other to the deck-stool, the revoluble member thrust-journalized in a bearing swiveled for universal movement, and the non-revoluble member also swiveled for universal movement.

In testimony whereof I affix my signature in presence of two witnesses.

HAROLD FREDERICK NORTON.
